UNITED STATES PATENT OFFICE.

EDWIN E. SLICK AND EMIL C. DANNER, OF PITTSBURGH, PENNSYLVANIA, ASSIGNEES
TO ROLLO STROP COMPANY, OF PITTSBURGH, PENNSYLVANIA, A CORPORATION OF
PENNSYLVANIA.

RAZOR-BLADE STROPPER.

Application filed March 9, 1921. Serial No. 450,859.

To all whom it may concern:

Be it known that we, EDWIN E. SLICK and EMIL C. DANNER, citizens of the United States, and residents of Pittsburgh, in the county of Allegheny and State of Pennsylvania, have invented certain new and useful Improvements in Razor-Blade Stropers, of which the following is a specification.

10 This invention relates to razor blade sharpeners and more particularly to razor blade sharpeners adapted to strop and sharpen the blades of safety razors, and has for one of its objects the provision of such 15 a device that may be manually operated and one that will operate on different forms of razor blades.

Another object is to provide a sharpener of this class having a novel blade holder 20 adapted to present the blade to the sharpening strops.

A further object is to provide a sharpener that will be compact, efficient and durable, with a minimum number of moving parts.

25 The above and other objects will be fully brought out in the following specification and illustrated in the accompanying drawings, in which:

Figure 1 is a side elevation of a razor 30 blade strop or sharpener constructed in accordance with this invention.

Figures 2 and 3 are sectional elevations showing the blade holder and blade in different positions.

35 Figure 4 is a side elevation showing the retaining member for the blade holder positioned to permit the removal of the blade holder.

Figure 5 is a sectional plan on the line 40 V—V of Figure 1.

Figures 6, 7, and 8 are detail views of the blade holder.

Figure 9 is a side elevation of a slightly modified construction of a strop adapted 45 for use with single edge blades.

Figure 10 is a sectional elevation of the strop of Figure 9.

Figure 11 is a side elevation of another modified construction of the strop.

50 Figure 12 is a sectional elevation of the strop of Figure 11.

Figure 13 is a sectional plan on the line XIII—XIII of Figure 11.

Figure 14 is a forward end elevation of the strop of Figure 11.

Referring particularly to Figures 1 to 8 of the drawings, the numeral 2 designates the body portion as a whole which comprises side plates 3 and 3^a which are secured together in spaced relation by spacer rods arranged in two series A and B, one series being located on each side of the central axis of the body portion. Each of the series of spacer rods A and B consists of three rods 4, 5, and 6, two of rods, 4 and 5 of each series, are located on the same vertical plane adjacent the top and bottom edges of the side plates and the third rod 6 is off-set toward the outer end of the plates and spaced equi-distant between the other rods 4 and 5.

Each of the rods 4, 5, and 6, carries a roller 7 to form an anti-friction mounting for the stropping member composed of strops 8 and 9.

The central portion of the side plates 3 and 3^a are cut away between the series of rods forming central passages or apertures 10 and 11, respectively, through which the blade holder 12 is adapted to pass and be reciprocated vertically. The apertures 10 and 11 are provided with vertical side walls 13 and 14, respectively, which guide and center the blade holder 12, as will be hereinafter more fully described.

The strops 8 and 9 are secured together at their ends by eyelets 15 and 16 and are trained about the rollers on the series of rods A and B, respectively. The strops 8 and 9 extend under the roller 7 on the rod 6 and over the roller 7 on the rod 5, thereby presenting upper and lower contacting surfaces or sharpening surfaces adapted to contact with a blade held in the holder 12, which extend horizontally within the body 2 of the device and at right angles to the length of the strops. The sharpener is adapted to be suspended from a hook, nail or other device by the eyelet 15 and is provided with a flexible member such as a cord loop 17 secured in the eyelet 16 to form a hand hold for the operator.

It will be obvious to those skilled in the art that a single strop may be substituted for the two strops 8 and 9 by doubling such strop upon itself at its center, instead of

securing two strops together by the eyelet 15.

The blade holder 12 comprises a top plate 18 and a bottom plate 19 adapted to clamp 5 a blade therebetween. The top member 18 is provided at one end with a pair of outwardly extending flat ears 20 which are adapted to abut the side edges 13 of the aperture 10 in the one side plate 3 to guide 10 the holder when it is reciprocated vertically. The ears 20 are off-set above the upper face of the plate 18 to prevent transverse movement of the bottom plate 19. The other end of the base plate 18 is provided with a pair 15 of ears having flat bottom portions 21 and upstanding portions 22. The bottom portions 21 of the ears are adapted to abut the side edges of the aperture 11 in the side plate 3^a and the upstanding portion 22 is 20 of greater width than the portion 21 and adapted to abut the side face of the plate 3^a to limit the transverse movement of the blade holder in one direction.

The top plate 18 has its one end turned 25 back upon itself in spaced relation forming a catch 23 adapted to receive the one end of the bottom plate 19. The other end of the bottom plate 19 is turned back upon itself in spaced relation, forming a catch 24 30 to receive the unturned end of the top plate 18, thus firmly locking the plates 18 and 19 together.

The top plate 18 is struck up to provide 35 rounded projections 25 adapted to be engaged in suitable apertures in the razor blade being sharpened, and the bottom plate 19 is provided with elongated slots 26 adapted to fit around the projections 25 and allow the plate 19 to bear against the blade.

40 The plates 18 and 19 are each provided on their one end with concave finger grips 27 and 28, respectively, to provide a grip for the operator when moving the sharpener along the strop.

45 A locking disk 29 is journaled on the side plate 3^a adjacent the aperture 11 and is cut away at one side of its vertical axis, the uncut portion being adapted to overlap the aperture 11 and lock the blade holder within the body of the sharpener.

50 In operation, a blade is clamped between the plates 18 and 19 of the blade holder and the holder is passed through the apertures 10 and 11 so as to lie within the body of the sharpener. When the blade holder is 55 positioned within the body of the sharpener the upstanding ears 22 will abut the side face of the plate 3^a and the locking disk 29 is rotated on its pivot so as to overlap one 60 of the ears 22 thus locking the holder in place.

65 After the blade holder is locked in position the operator grasps the finger grips 27 and 28 and moves the sharpener along the strops 8 and 9 which have their one end se-

cured to a hook or other permanent fixture. As the operator moves the sharpener along the strops in the up direction the blade holder and blade will be forced up against the upper contacting surfaces of the strops 70 and as the movement of the sharpener is reversed in the down direction the blade holder will be reciprocated so as to bear against the lower contacting surface of the strops 8 and 9, thus stropping or sharpening both 75 sides of the blade edge.

In Figures 9 and 10 a modified form of sharpener is shown for use in sharpening single edge blades. The construction of this modified form is the same as the preferred form described above with the exception that the series of tie rods B and the rollers carried thereby are omitted, and but the one strop 8 used for sharpening the blade. Two tie rods 30 and 31 are substituted for the series of rods B to tie or hold the forward end of the side plates 3 and 3^a together.

In Figures 12 to 14 we have shown a further modified construction for sharpening 90 or stropping a double edge blade. Referring to this modification the numerals 33, 34 designate the respective side plates which are held in spaced relation by the rods 35, 36, and 37. The rods 35 and 36 are mounted on the same vertical plane adjacent the forward edge of the plates, and the rod 37 is mounted adjacent the rear edge of the plates and midway between the horizontal axis of the rods 35 and 36. Each of the rods 35, 36, and 37 carry a roller 38, and a strop 39 is adapted to be trained under the roller on the rod 36, over and around the roller on the rod 37 and over and around the roller on the rod 35, thereby presenting upper and lower contacting or sharpening surfaces adapted to contact with a blade held in the blade holder 40 to be described.

The blade holder 40 comprises a bottom plate 43 and a top plate 47. Each of the plates 43 and 47 is provided at one end with a crank shaped operating arm 44 which is permanently secured thereto. The arms 44 have their lower or plate engaging ends 45 formed cylindrical and bifurcated to provide a spring construction which will permit of them being compressed sufficiently to pass through the slots 41 and spring into the bearings 42. The free ends of the plates 43 and 47 are adapted to be sprung into the bifurcated ends 45 of the arms 44 to hold the plates together.

The lower plate 43 is struck up to provide retaining lugs 46 adapted to project through suitable apertures in the blade being sharpened, to center and hold said blade in position.

The outer terminals of the arms 44 are each provided with concave finger grips 48 to provide a grip for the operator in mov-

ing the device along the strap and reciprocating or rocking the blade.

The operation of this modified form will be readily understood. The blade holder is forced out of the slots 41 and a blade clamped therein. The blade holder is then forced back through the slots 41 until the ends 45 of the arms 44 are engaged in the bearing portions 42 of the slot. The operator grasps the finger grips 48 and moves the device back and forth along the strap 39 and as the movement is reversed the blade holder will rock in the bearing portion 42 of the slots 41, thus presenting the opposite sides of the blade edges to the strop.

While we have shown and described certain preferred forms of our invention it will be understood that we do not wish to be limited to such specific constructions since various changes in construction and combination of parts may be made without departing from the spirit of this invention as defined in the appended claims.

We claim:

1. A razor blade sharpener comprising a flexible stropping member, a body portion mounted on said stropping member for reciprocation relative thereto, supports in said body portion for said stropping member, said stropping member being trained over said supports in said body portion so as to present upper and lower stropping surfaces, and a blade holder adapted to be reciprocated within said body portion perpendicular to said stropping surfaces so as to cause both edges on one side and both edges on the other side of a double blade carried thereby to contact alternately with the upper and lower stropping surfaces of said stropping member.

2. A razor blade sharpener comprising a body portion having a plurality of rollers journaled therein, at least one strop trained about said rollers so as to present upper and lower parallel stropping surfaces extending horizontally within said body portion and substantially at right angles to the length of the strop, a blade holder mounted in said body portion and adapted to be manually reciprocated perpendicular to said stropping surfaces to cause a blade carried thereby to contact alternately with the upper and lower stropping surfaces of the strop, said body portion being adapted to be manually reciprocated on said strop.

3. A razor blade sharpener comprising a body portion having two sets of rollers journaled therein, one of said sets of rollers being on each side of the central axis of the body and each set comprising three independent rollers, a stropping member trained about said rollers so as to present upper and lower parallel stropping surfaces extending substantially at right angles to the length of the stropping member, a blade holder de-

tachably mounted in said body portion and adapted to be reciprocated to engage a blade carried thereby alternately with the upper and lower stropping surfaces of said stropping member.

4. A razor blade sharpener comprising a body portion having two sets of rollers journaled therein, one of said sets of rollers being on each side of the central axis of the body and each set comprising three independent rollers, a stropping member trained about said rollers so as to present upper and lower parallel stropping surfaces extending substantially at right angles to the length of the stropping member, a blade holder mounted in said body portion and adapted to be manually reciprocated with relation to said body portion to cause a blade carried thereby to contact with the upper and lower stropping surfaces of said stropping member, said sharpener being adapted to be manually reciprocated on said strop.

5. A razor blade sharpener comprising a roller frame having a flexible stropping member mounted thereon to form two upper and two lower stropping surfaces, and a blade holder mounted therein, said frame being arranged to reciprocate on the stropping member and said holder being arranged to reciprocate in the frame perpendicular to said stropping surfaces in sharpening the blades.

6. A razor blade sharpener comprising a flexible stropping member, a frame member mounted on said stropping member and movable longitudinally thereon, supports in said frame member for said stropping member, said stropping member being trained over said supports in said frame member to form upper and lower stropping surfaces extending parallel to each other, and a blade holder loosely mounted in said frame member and adapted to be manually raised and lowered in a path perpendicular to said stropping surfaces so as to bring both edges of the opposite sides of a double edge blade thereon alternately into contact with said stropping surfaces.

7. A razor blade sharpener comprising a flexible stropping member, a frame member mounted on said stropping member and movable longitudinally thereon, a plurality of supporting rollers journaled in said frame, said stropping member being trained over said rollers to form upper and lower stropping surfaces extending parallel to each other, and a blade holder loosely mounted in said frame member and adapted to be manually raised and lowered in a path perpendicular to said stropping surfaces so as to bring both edges of the opposite sides of a double edge blade thereon alternately into contact with said stropping surfaces.

8. A razor blade sharpener comprising a body portion having a pair of strops mount-

ed therein so as to present upper and lower stropping surfaces, a blade holder adapted to be reciprocated within said body portion perpendicular to the stropping surfaces so as to cause a blade carried thereby to contact alternately with the upper and lower stropping surfaces of said strops, and means on the ends of said blade holder adapted to be engaged by the operator to reciprocate said holder.

9. A razor blade sharpener comprising a body portion having a pair of strops mounted therein so as to present upper and lower stropping surfaces, a blade holder adapted to be reciprocated within said body portion perpendicular to the stropping surfaces so as to cause both edges on one side and both edges on the other side of a double edge blade carried thereby to contact alternately with the upper and lower stropping surfaces of said strops, and means on the ends of said blade holder adapted to be engaged by the operator to reciprocate said holder.

10. A razor blade sharpener comprising a body portion having a pair of strops mounted therein so as to present upper and lower stropping surfaces, a blade holder adapted to be reciprocated within said body portion perpendicular to the stropping surfaces so as to cause both edges on one side and both edges on the other side of a double edge blade carried thereby to contact alternately with the upper and lower stropping surfaces of said strops, and disks on the ends of

the holder adapted to be engaged by the operator to reciprocate said holder.

11. A razor blade sharpener comprising a body portion having a pair of strops mounted therein so as to present upper and lower stropping surfaces, a blade holder adapted to be reciprocated within said body portion perpendicular to the stropping surfaces so as to cause both edges on one side and both edges on the other side of a double edge blade carried thereby to contact alternately with the upper and lower stropping surfaces of said strops, said body portion being adapted to be reciprocated on said strops, and concave disks on the ends of said blade holder adapted to be engaged by the operator to reciprocate said holder and said body portion.

12. A razor blade sharpener comprising a body portion having a stropping member mounted therein so as to present upper and lower stropping surfaces, a blade holder adapted to be reciprocated within said body portion so as to cause a blade carried thereby to contact alternately with the upper and lower stropping surfaces of said stropping member, and means on the ends of said blade holder adapted to be engaged by the operator to reciprocate said holder.

In testimony whereof, we have hereunto set our hands.

EDWIN E. SLICK.
EMIL C. DANNER.
